(57) **CLAIM**

The ornamental design for an oval pan, as shown and described.

DESCRIPTION

FIG. 1 is a front, right perspective view of an oval pan showing my new design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

The portions of the drawings illustrated in broken lines are directed to the boundary of the design and form no part of the claimed design.
